WALL PAPER.

No. 17,671.

Patented Aug. 30, 1887.

UNITED STATES PATENT OFFICE.

ROBERT H. PRATT, OF NEW YORK, N. Y.

DESIGN FOR WALL-PAPER.

SPECIFICATION forming part of Design No. 17,671, dated August 30, 1887.

Application filed July 5, 1887. Serial No. 263,477. Term of patent 3½ years.

To all whom it may concern:

Be it known that I, ROBERT H. PRATT, a citizen of the United States, residing at New York, in the county of New York and State of New York, have invented a certain new and original Design for Wall-Papers; and I do declare the following to be a full, clear, and exact description of the invention, such as will enable others skilled in the art to which it appertains to make and use the same, reference being had to the accompanying drawing, and to the letters and figures of reference marked thereon, which form a part of this specification.

The invention relates to certain new and original designs for wall-papers, and is of a conventional style and of the tapestry description, and will be hereinafter more particularly described and claimed, reference being had to the accompanying drawing, forming a part hereof, and in which is illustrated the invention.

The design is made up of flowers, buds, and ornamental scrolls inclosing the same, to which effect is given by lines extending across the scrolls and also the buds and flowers.

To more particularly describe the design, there is a central flower or bud, A, around which are four other and preferably smaller buds, B. Two ornamental scrolls, C, converge toward the lower portion of the central bud, and then, after diverging again, converge toward the next lower central bud, these scrolls in their course passing outside of two of the small buds and then between the other two buds and the central bud. One set of scrolls, D, branch from the scrolls C and then return and entwine said scrolls, and another set, E, branch from the same scrolls, C, and curve or curl around the buds B, as shown. The scrolls D and E inclose a space, F, having four corners and concave sides, and in that space is formed a flower, G, of a bell-shaped figure.

The scrolls and flowers and buds may have small or narrow lines *a*, which may be of a golden color, extending across portions of the figures. The ground of the figures proper may be of a steel color, while the ground of the paper may be a canary color, and the outline or border-line of the figures a darker shade.

The design has also been described with considerable particularity, but only for fullness and clearness, without so far limiting the design as not to cover substantially the same and colorable imitations thereof.

Having described the invention, what is claimed is—

1. The design for wall-papers, consisting of a central flower or bud with other buds around it and ornamental scrolls curving between and around the buds, substantially as shown and described.

2. The design for wall-papers, consisting of a central flower or bud with other buds around it, ornamental scrolls C, converging and diverging from each other, scrolls D, branching from scrolls C and entwining around them, scrolls E, branching from scrolls C and curling around the outside buds, and a flower inside the space inclosed by the scrolls D and E, substantially as shown and described.

3. The design for wall-papers, consisting of a central flower or bud with other buds around it, ornamental scrolls curving between and around the buds, and narrow lines extending across said flowers or buds, substantially as shown and described.

In testimony whereof I affix my signature in presence of two witnesses.

ROBERT H. PRATT.

Witnesses:

THEODORE CHATTERTON,
GEO. HAMANN, JR.
